PRINTING MACHINE FOR MARKING
ARTICLES

Philip N. Braun, Syracuse, N. Y.

Application October 28, 1948, Serial No. 57,080

1 Claim. (Cl. 101—95)

1

This invention relates to printing machines of the class for printing identifying characters on articles to be laundered, or dry cleaned, or on tags to be applied to such articles, and has for its object means by which the platen on which the tags or the articles are carried is actuated momentarily by power as the platen approaches the printing line of the machine but is still short of the printing line in order that the force applied to the platen will always be substantially equal and hence, the imprint on the tags or articles uniform. It will be understood that it is important that the imprinting be uniform in order to avoid fading out of the imprint during the laundering, or dry cleaning operation.

The invention consists in the novel features and in the combinations and constructions hereinafter set forth and claimed.

In describing this invention, reference is had to the accompanying drawings in which like characters designate corresponding parts in all the views.

Figure 1 is a fragmentary front elevation of a printing machine embodying this invention.

Figure 2 is an elevation, partly in section, looking to the right in Figure 1.

The construction of the printing machine per se forms no parts of this invention.

The numeral 1 designates type carrying elements or wheels having type 2 on their peripheries, the wheels being movable by hand independently of each other to bring selected type to the printing line. The wheels are mounted in a casing 3 on a horizontal axis.

4 designates a platen which is mounted on a carrier 5 having a forward movement from starting position to carry the platen with the work thereon toward the printing line, and a rearward movement back to starting position. As here shown, the carrier 5 is pivoted at 6 to a sub-frame 7 mounted in the front portion of the casing 3 at a point below the plane of the horizontal axis of the printing line, the carrier having handles 8 extending laterally from opposite sides thereof by means of which the carrier is moved forwardly and rearwardly. In printing an identifying character on articles, a portion of the article is held taut over the platen by the operator gripping the article in both hands about the handles 8.

9 designates a ribbon mechanism, this including a ribbon guide 10 arranged to guide a portion of the ribbon across the printing line. The ribbon mechanism is actuated to feed the ribbon during each operation of the platen carrier 5 in

any manner, and the ribbon and the ribbon feed mechanism form no part of this invention.

This invention comprises a motor normally ineffective on the platen carrier 5, and means operated by the movement of the platen carrier by hand from the starting position to make the motor momentarily effective on the platen carrier as the platen approaches but is short of the printing line, and also for rendering the motor ineffective on the platen carrier when the platen reaches the printing line, all so that the platen is momentarily actuated by power in order that the imprints made on the articles or tags being printed will be uniform.

15 The motor here illustrated is an electromagnet 11 mounted on a bracket 12 in the bottom of the casing 3 below the platen carrier. The magnet is effective on an armature 13 carried by the platen carrier and normally out of the field of the magnet and movable into the field of the magnet when the platen carrier 5 is actuated forwardly by the operator into a position where it is approaching but still short of the printing line. As shown, the armature 13 is carried by a radial arm 15 of the platen carrier 5, which arm normally extends upwardly and forwardly from the axis of the platen carrier 5. The arm 15 also carries a weight 16 tending to move the carrier 5 forwardly on its pivot about its pivotal shaft 6. The motor or magnet 11 is normally idle or de-energized, and is controlled in its energization by the manual forward movement of the carrier 5, the control means being a normally open, self-opening switch in the magnet circuit, and being momentarily closed by the forward movement of the platen carrier 5.

17 designates the switch having an operating member or push button 18. The switch is mounted in the lower front portion 1 of the casing 3 in position to be operated by the platen carrier 5. It is here shown as operated by an arm 19 pivoted at 20 to the front portion 7 of the casing and as having its end remote from the pivot pressing on the push button 18. The switch itself is of the type which is self opening. The arm 19 has a laterally extending pin or arm 19^A arranged in the path of a shoulder 21 on one side of the platen carrier and located to sweep over the upper edge of the arm 19 during the forward movement of the platen 5 from starting position and engage the upper surface of the pin arm 19^A and depress the arm 19 and hence, close the switch 17 after the platen carrier has moved forward a predetermined distance, this being 55 when the platen 4 is approaching but is short of

the printing line, the shoulder 21 passing off or clearing the pin 19^a about when the platen carrier reaches the printing line and strikes the blow in pressing the article and the ribbon against the type at the printing line. The shoulder 21 is of such shape as wedge shape (Figure 2) that it passes under the pin 19^a during the return movement of the carrier 5, and hence does not close the switch 17.

When the switch is closed, the armature 13 has been shifted by the carrier into the field of the magnet 11 and hence, when the switch is closed the magnet is energized and pulls the armature downwardly, thus applying power to the platen carrier 5 to strike the printing blow.

23 and 24 designate the service wires for the magnet and in which the control switch 17 is connected. By reason of the motor or magnet 11, the blow struck by the platen is always uniform. This blow is not interfered with by the operator's hands unless the operator wilfully and unnaturally tries to interfere with the action of the carrier by the magnet 11. In case of printing tags from a strip, the operator merely gives a flip to the handle 5 and it is not necessary to grasp the handles 8. When the operator is gripping the article while gripping the handles 8 to hold the article taut over the platen, he applies very little operating or hold back force to the platen carrier.

What I claim is:

In a printing machine of the class described which includes a frame, type carrying elements supported by the frame and shiftable to bring different type to a horizontal printing line, a platen on which the article to be printed is carried, a carrier for the platen comprising a lever

pivoted to the frame on a horizontal axis spaced from and below the level of the printing line and carrying the platen at its upper end, the lever being movable on its pivot to carry the platen toward and from the printing line, an electro-magnet located in the lower portion of the frame, the platen carrying lever having an angular arm extending over and normally spaced from the electro-magnet, the magnet having an armature fixed to said arm, the spacing of the arm and the magnet being such that the armature is normally out of the field of the electro-magnet and movable into the field as the platen carrier approaches printing position, a feed circuit for the electro-magnet having a normally open switch therein, and switch closing means carried by the platen carrier lever and movable during the movement of the platen to printing position to momentarily close the switch.
